DESIGN.

—o—

J. L. FOLSOM.

CARPET.

No. 17,970.

Patented Dec. 20, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,970, dated December 20, 1887.

Application filed September 21, 1887. Serial No. 230,637. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be worked 10 into or upon surfaces, such as carpets or similar fabrics; and it consists in the novel configuration and grouping of figures herein specifically shown and claimed.

The accompanying photograph is a face view 15 of a carpet showing my new design.

My design consists of the figures A, B, and C, disposed at intervals over the surface of the carpet, substantially as shown.

Figure A has an underlying conventionalized stem-work with branches projecting therefrom. Upon this stem-work are supported several conventionalized circular flower forms. At one portion of the figure there is a mass of block-work ornamentation, over which is scattered a series of cross-shaped forms. Smaller 25 stems project here and there from the sides of the figure, bearing small leaves.

Figure B has an irregular stem-work bearing circular flower forms of a somewhat skeleton-like character. Connected with the stem-work is a mass of block-like ornamentation quite irregular in the form and arrangement of its parts.

Figure C is a smaller figure. At its center is a mass of irregularly-shaped blocks. From one side of this mass projects a thick short stem-work. A few small stems and separate ornaments are scattered around the borders of the figure.

These figures are arranged upon a ground-work having at irregular intervals groups or portions of cellular-like work.

What I claim as new, and desire to secure by Letters Patent, is—

1. The design for carpets, consisting of the figure B, substantially as shown.
2. The design for carpets, consisting of the figures A, B, and C and the groundwork, substantially as shown.

JAS. L. FOLSOM.
